(57) **CLAIM**

The ornamental design for an audio appliance for television, as shown and described.

DESCRIPTION

The patent or application file contains at least one drawing executed in color. Copies of this patent or patent application publication with color drawing(s) will be provided by the Office upon request and payment of the necessary fee.

1. Audio appliance for television

1.1 : Front

1.2 : Back

1.3 : Left

1.4 : Right

1.5 : Top

1.6 : Bottom

1.7 : Perspective

1.1-1.7 are drawings showing the embodiment of the audio appliances for television; the present product is used for playing audio. The blue marked parts with broken lines boundaries thereof form no part of the claimed design.

1 Claim, 7 Drawing Sheets
